(57) **CLAIM**

The ornamental design for an electronic display screen with a graphical user interface, as shown and described.

DESCRIPTION

The FIGURE illustrates a front view of an electronic display screen with a graphical user interface.

The outermost broken-line rectangle illustrates an electronic display screen and forms no part of the claimed design. The broken lines illustrating the symbol in the center of the three arcuate segments and the camera icon in the upper right segment form no part of the claimed design. The differing line patterns in the FIGURE illustrate a contrast in appearance. The longer dashed lines in the bottom arcuate segment of the graphical user interface illustrate a contrast in appearance and are included in the claimed design.
